BUOYANT LIFE PRESERVER

Edgar G. Baker, Carbondale, Pa., assignor to General Textile Mills, Inc., New York, N. Y., a corporation of Delaware

Application November 15, 1955, Serial No. 38,908

Term of patent 14 years

(Cl. D71—1)

Figure 1 is a plan view of my buoyant life preserver showing my new design.

Figure 2 is a side elevation of the buoyant life preserver shown in Figure 1.

Figure 3 is a perspective view of the buoyant life preserver shown in Figure 1.

The essential features of my design reside in the portions shown in full lines.

I claim:

The ornamental design for a buoyant life preserver, substantially as shown and described.
